(57) **CLAIM**

USPC **D10/104.1**

The ornamental design for a wearable personal identification device, as shown and described.

DESCRIPTION

(58) **Field of Classification Search**

USPC ... D14/344, 138 R, 144, 341, 358, 485-489, FIG. 1 is a perspective view of a wearable personal identification device showing our new design;

D14/480.1, 480.4; D10/30-39, 70, 98, FIG. 2 is a front view of the wearable personal identification device;

D10/104.1; D11/3, 93-94, 79; D24/167,

D24/169, 186-187; 361/679.03;

379/433.1; D21/683; D8/347

CPC .. A41D 1/002; G06F 1/04; G06F 1/08; G06F

1/10; G06F 1/14; G06F 1/1626; G06F

1/1628; G06F 1/163; G06F 1/1635; G06F

1/3203; G06Q 20/10; G06Q 20/12; G06Q

20/108; G06Q 20/145; H04B 1/3833;

H04B 1/385; H04B 1/3888; H04M 1/02;

H04M 1/03; H04M 1/04; H04M 1/05;

FIG. 3 is a rear view of the wearable personal identification device;

FIG. 4 is a left side view of the wearable personal identification device;

FIG. 5 is a right side view of the wearable personal identification device;

FIG. 6 is a top view of the wearable personal identification device; and,

(Continued)

FIG. 7 is a bottom view of the wearable personal identification device.
